UNITED STATES PATENT OFFICE.

EDWARD FERRISS, OF NAPOLEON, NORTH DAKOTA.

SLEIGH.

No. 901,604.

Specification of Letters Patent.

Patented Oct. 20, 1908.

Application filed April 27, 1908. Serial No. 429,491.

To all whom it may concern:

Be it known that I, EDWARD FERRISS, a citizen of the United States, residing at Napoleon, in the county of Logan and State of 5 North Dakota, have invented certain new and useful Improvements in Sleighs; and I do hereby declare the following to be a full, clear, and exact description of the invention, such as will enable others skilled in the art to 10 which it appertains to make and use the same.

My invention has for its object to provide a simple, strong, and durable cutter or sulky 15 sleigh of cheap construction and good design; and to this end it consists of the novel devices and combinations of devices herein-after described and defined in the claims.

The invention is illustrated in the single perspective view of accompanying drawing. 20 This improved cutter, or so-called sulky sleigh, is preferably constructed entirely of metal. The frame-work of the sleigh is constructed from a single steel rod bent in an approximately horizontal plane to form a 25 front yoke 1, a rear yoke 2, and laterally spaced vertically disposed side coils or hoops 3. These side hoops 3 form the side frames and runner supports of the sleigh, and to the 30 lower portions of which steel runners 4 are rigidly secured at their forwardly up-turned ends. The overlapping portions of the 35 hoops 3 are rigidly tied together by metallic clips 5 and, as shown, the ends of the rod from which the said parts are formed are brought together and overlapped at the front 40 of the yoke 1 and are connected, by a nutted bolt 6, to the pole 7. The rear end prongs 7^a of the pole 7 are shown as connected, by coupling brackets 8, to the forward portions 45 of the hoops 3, so that the tongue is rigidly secured to the frame of the sleigh. Of course, thills or shafts may be connected to the said frame in substantially the same manner or by slightly modified connections.

45 The bottom 9 of the sleigh body is rigidly connected to a dash-board 10, to side plates 11, and to a seat 12, and all of these parts are rigidly secured to the upper portions of the 50 hoops 3 and to the rear yoke 2. It will be

further noted that the side plates 11 are extended directly in and are secured directly to the curved portion of the rear yoke 2 to form a back for the seat 12.

A cutter or sleigh constructed as above described and as illustrated in the drawings 55 will be very light, strong and durable, and, at the same time, has a novel and ornamental appearance. Furthermore, it may be built at small cost. On account of its extreme lightness and rigidity, such a cutter or so-called sulky sleigh will be found extremely well adapted for use for racing purposes and for breaking horses. It is, however, well adapted for general use wherever a small and light sleigh, either for a single horse or team, 65 is desired.

What I claim is:

1. A sleigh having a frame formed from a metallic rod or bar bent to form horizontal front and rear yokes and laterally spaced depending hoops, and provided with a body secured thereto.

2. A sleigh having a frame constructed from a single metal rod bent to form horizontal front and rear yokes and laterally spaced depending hoops, runners connected to the lower portions of said hoops, and a body connected to said frame-work, substantially as described.

3. A cutter having a frame constructed 80 from a metal rod bent to form front and rear yokes and laterally spaced hoops, runners applied to the lower portions of said hoops, clips rigidly secured to the overlapped upper portions of said hoops, and a body made up 85 of a bottom, an up-turned dash-board and a seat, the said parts being rigidly secured to said frame-work, and the back of said seat being directly secured to and depending from the rear yoke of said frame, substantially as described.

In testimony whereof I affix my signature in presence of two witnesses.

EDWARD FERRISS.
